UNITED STATES PATENT OFFICE

DANTE O. TEMPESTINI, OF NEW ORLEANS, LOUISIANA

BOX-STAMPING MACHINE

Application filed April 11, 1930. Serial No. 443,544.

This invention relates to a machine for stamping boxes of merchandise or any other rectangular containers of merchandise, and has as its general object to provide a machine, 5 extremely simple in construction and adapted to operate automatically to impress upon the opposite sides of the boxes or other containers any desired advertising matter, the name of the goods, or any other matter, the 10 machine being so constructed that the boxes may be fed through the machine either before the merchandise has been packed therein or after the boxes have been packed and sealed.

15 Another object of the invention is to provide in a machine for the purpose stated, an arrangement of printing rolls and a feeding means for feeding the boxes between the rolls, the component parts of these means 20 being so arranged and operated as to insure of accuracy in impressing the matter to be printed upon the sides of the boxes.

Another object of the invention is to provide a machine of this class in which the 25 printing rolls may be readily adjusted so as to cause them to bear with any desired degree of firmness against the opposite sides of the boxes, depending upon the dimensions of the boxes.

30 This invention also consists in certain other features of construction and in the combination and arrangement of the several parts, to be hereinafter fully described, illustrated in the accompanying drawings, and 35 specifically pointed out in the appended claims, it being understood of course that minor changes may be made so long as they fall within the scope of the claims.

40 In describing my invention in detail, reference will be had to the accompanying drawings wherein like characters denote like or corresponding parts throughout the several views, and in which:—

45 Figure 1 is a view in side elevation of the printing machine embodying the invention, a box being shown in position at the beginning of the impressing operation.

Figure 2 is a top plan view of the ma- 50 chine.

Figure 3 is a view in end elevation of the machine.

Figure 4 is a view in elevation illustrating the printing roller and a part of the means for rotating the same and the ink 55 feeding unit of the machine.

Figure 5 is a diametric sectional view taken substantially on the line 5—5 of Figure 4 looking in the direction indicated by the arrows.

Figure 6 is a schematic view of the means for supplying ink to one of the ink feeding rollers.

Figure 7 is a vertical sectional view likewise illustrating a part of the ink feeding 65 mechanism.

Figure 8 is a horizontal sectional view on the line 8—8 of Figure 7, looking in the direction indicated by the arrows.

Figure 9 is a perspective view illustrating, in a general way, a part of the mechanism provided for feeding the boxes past the impression rollers.

The machine comprises a supporting 75 frame structure which is indicated in general by the numeral 1 and which may be of any structure found suitable for the purpose, and this frame structure supports a top member 2 which is provided at opposite sides of its longitudinal middle with upstanding parallel guides 3 between which the boxes to be printed are fed, these guides being located at one side of the transverse middle of the top member 2 of the machine and other guides 4 being arranged at the other or delivery side of the said top, corresponding guides being in longitudinal alignment and spaced at their relatively adjacent ends.

85 The impression rolls are indicated in general by the numeral 5 and each of these rolls comprises a cylindrical body 6 which may be made of wood or any other suitable material found suitable for the purpose, and the body is surrounded by a circumferential impression band 7, which is preferably seated in a recess 8 formed circumferentially in the body, and this impression band may 90 be of rubber or of metal, depending upon the character of the boxes upon which the im- 95

pressions are to be made. Each roller is supported, by a spindle 9, for rotation above the surface of the top 2 of the frame, and in mounting the rollers bearing blocks 10 are 5 slidably mounted in boxings 11 of tubular form, and the ends of the spindles are journaled in the said blocks. The boxings are mounted at one end upon an upright 12 upon the top member 2 at one side of the 10 impression roller, and the boxings are formed with longitudinal slots 14 to accommodate the shaft ends, the bearings blocks being movable in the boxings. Plugs 16 and 17 are mounted in the ends of the 15 housings, the plug 16 in that end of each housing which is mounted on the upright 12 and the plug 17 in the other end of each housing, and compression springs 18 and 19 are arranged in each housing and bear, 20 at their inner ends against opposite sides of the bearing block 10 and, at their outer ends, respectively against washers at the ends of adjusting screws 20 and 21 which are mounted in the plugs 16 and 17, respectively, it being understood that the 25 tension of the springs 18 and 19 may be suitably varied by the adjustment of these screws, so that, if a box having a warped side, or, a box which is slightly tilted is passing the impression roll, the roll will be permitted to move, with its spindle and bearings, so as to compensate for the bulging or tilting.

The inking rolls for each impression roll 30 are mounted upon a base 22 which is supported above the base 2, and one of the rolls is indicated by the numeral 23 and the other by the numeral 24. Mounted upon the base 22 is a housing 25, and the roll 23 is mounted 35 upon a shaft 26, within the housing 25, and one side of the roll is presented exteriorly of the housing so as to be in surface contact with the roll 24, the roll 24 being mounted in a manner which will presently be explained. 40 In order that ink, supplied to the surface of the roll 23, may be delivered from this roll to the surface of the roll 24 in a uniform film and without waste of ink, the housing 25 is formed in that side wall at which the 45 roll 23 is mounted, with a rectangular opening 27, and disposed against the outer face of this wall of each side of the opening 27 is a baffle plate 28 which is provided with slots 29 through which pins 30, secured to the 50 said side wall of the housing, are engaged, and each of the blades 27 is provided at its outer edge with a vertically extending flange 31, and adjusting screws 32 are threaded adjustably through the openings 33 in the respective end walls of the housing 25, and at this point it will be understood that by adjusting the screws 31, the baffle plates 28 may be adjusted so as to bring their relatively adjacent vertical edges, which project inwardly 55 from the opposite side of the opening 27,

into light contact with the surface of the roll 23. It will therefore be seen that as the roll 23 is rotated, ink which is supplied to the surface thereof by a means to be presently described, will be spread, by the edges of the baffle plates 28, so as to supply to the surface of the roll 24, a film of ink of the uniform density.

The means, referred to above, for supplying ink to each roll 23, comprises an ink reservoir, indicated in general by the numeral 34 and this ink reservoir is preferably of the cylindrical form shown in the drawings, and is mounted at the upper end of an ink feeding pipe 35 which extends downwardly within the housing 25 to the lower end thereof and is preferably supported at its lower end upon the bottom of the housing and this pipe is formed with a vertically extending slot 36 and it is through this slot that ink, delivered from the reservoir 34, is supplied to the roll 23. It will be observed by reference to Figure 8 of the drawings, that the ink supply tube 35 is disposed at one side of the roll 23 and near that side wall of the housing 25 which is presented toward the impression roller 5. By reference to Figure 4 of the drawings as well as to Figures 1 and 2, it will be observed that the roll 24 is mounted upon a spindle 37 for rotation about said spindle, and tension springs 38 are connected to the upper and lower ends of the spindle and at their other ends to rivets or the like indicated by the numeral 39, and located upon the top of the housing 25 and under side of the base 22, respectively. The said upper and lower ends of the spindle 27 work in notches 40 in flat relatively narrow and elongated plates 41 which are mounted at their ends opposite their ends in which the notches are formed, upon the upper and lower ends of the spindle 9 for the corresponding print roller 5, and the said rollers 24 are, as shown in Figures 1, 2 and 4 of the drawings, in contact with the surfaces of the impression rolls 5, at the opposite sides of the machine.

As stated, the ink reservoir 34 is of cylindrical form and arranged within the reservoir of each ink supply unit of the machine, is a circular follower head 42 to the under side of which is secured an annular packing ring 43 of any flexible or semi-flexible material which is in contact at its outer margin with the inner surface of the circumferential wall of the reservoir. A stem 44 is secured at its lower end to the disk 42 axially thereof, and this stem extends upwardly through an opening in the cover for the open top of the reservoir, which cover is indicated by the numeral 45, and the opening through which the stem extends is threaded as also the stem, the latter as indicated by the numeral 46, and a hand wheel 47 is mounted upon the upper end of the stem 130

and provides means whereby the stem may be rotated so as to feed the follower head 42 downwardly in the reservoir and thus control the supply of ink through the slot 36 in the delivery pipe 35, to the respective roll 23. A spiral compression spring 48 is arranged about the stem 44 and bears at its lower or major upper end against the under side of the cover 45.

10 The feeding means for the boxes, referred to above, and likewise the means provided for rotating the impression rollers in consonance with the speed of feeding of the boxes, comprises two rack bars 49 which are 15 mounted at opposite sides of the base 2, and gears, mounted upon the lower ends of the shafts 9 of the respective rolls 5, are indicated by the numeral 50 and are, in mesh with the respective rack bars 49, and these 20 bars are disposed slidably in contact with the guides 3, heretofore referred to, and in order that the rack bars 49 may travel in a smooth and even manner, anti-friction rollers 51 are mounted in suitable bearings at 25 the under sides of the bars and these rollers travel over the surfaces of the base 2.

The inking rolls 23 and 24 are of course rotated through the rotation of the respective printing rollers 5 and the rollers 5 are 30 in turn rotated through the medium of a means to be presently described, and it will be understood from the foregoing that when the boxes are successively fed between the impression rollers, impressions will be simultaneously made on the opposite sides of each box.

The feeding means, referred to above, comprises two shafts indicated by the numerals 52 and 53 which are mounted in suitable 40 bearings upon the under side of the top 2 of the frame of the machine, and pairs of sprocket gears 54 and 55 are mounted upon the shafts 52 and 53, respectively.

The numeral 56 indicates a shaft which 45 is mounted below the shaft 52 in a vertical plane therewith, and fixed upon the shaft 52 is a gear 57 which is in mesh with a pinion 58 upon the shaft 56, a pulley 59 being likewise fixed upon the shaft 56 and a belt 60 being trained about this pulley and a pulley 61 of less diameter, upon the shaft 62 of an electric motor 63 which is mounted upon a base plate 64 supported adjustably by threaded uprights 65 located at one end of 55 the said plate and held in positions of vertical adjustment by means of nuts 66 threaded upon the said uprights, the other end of the plate being supported upon a bracket 67, mounted upon one end member of the frame 60 structure. In this manner rotary motion is imparted to the sprocket gear 53 and, through the medium of sprocket chains 60 to the sprocket gear 54, the chains being trained about respective ones of the respective sprocket gears 54 and 55.

The numeral 69 indicates a pair of arms which are riveted or otherwise secured, at their inner ends to corresponding links of the chains 68, so as to project outwardly from the said chains, and pressure rollers 70 are mounted at their ends at the outer ends of the arms 69, so as to be supported for rotation thereby.

In order that the arms and the rollers supported thereby may be carried by the 75 stretches of the chain 68 longitudinally of the machine, the machine top 2 is formed with a longitudinal opening 72, midway between the impression rolls 5, it being understood that the arms 69 and the rollers 70 supported thereby, may pass through this opening when travel is imparted to the sprocket chains 68.

As shown in Figure 9, the rack bars 49 are connected at one end by a transverse frame member 73 having an abutment portion 74 against which the rolls 70 are to engage and the abutment portion 74 is designed to engage against one end of the box to be printed as shown in Figure 1.

In the operation of the machine, the boxes, indicated by the reference character "B", are placed between the guides 3 and shoved forwardly over the top 2 and, as the sprocket chains 68 travel their upper stretches carry the arms 69 and the pressure roller 70 around the sprocket gears 54, and the roller 70 is brought into engagement with the abutment portion 74, as clearly shown in Figures 1 and 3 of the drawings. In the continued travel of the sprocket chains 68, the box is moved between the guides 3 and between the impression rolls and the opposite sides of the box are thus impressed with the matter which it is desired to display thereon.

After leaving the rollers 5, the box is still advanced over the surface of the top 2 through the medium of the roller 54 and abutment portion 74, and in the meantime, another one of the pushing units has been brought to position adjacent the sprocket gears 55, so as to be carried upwardly and into engagement with another box, which has been, in the meantime, disposed upon the top 2 between the guides 3. After delivery of the impressed boxes to position between the guides 3, the boxes may be removed from the said top 2.

It will be evident that inasmuch as the springs 38 serve to hold the inking rolls 24 in engagement with the rolls 23, the rolls 24 will only engage the surfaces of the impression rolls 5 at the portions thereof which bear the impressing characters in raised form, and therefore the faces of these characters will be the only portion of the rolls which will be impressed upon the sides of the boxes fed through the rolls and, likewise, these springs prevent the inking rolls 24 contacting the blank surfaces of the rolls 5

as the raised impressing characters on the rolls 5 pass the said rolls 24.

In order that the rack bars 49 may be automatically returned to their initial position, 5 after each box has travelled past the impression rolls 5, cables 75 are connected at one end as at 76, to one end of each rack bar and the cables are led beneath the rack bar toward the other end thereof and over 10 idle pulleys 77 which are suspended beneath the base 2, and each cable is then passed about an idle pulley 78 mounted at the upper end of a counter-weight 79 and then led upwardly and connected to a yoke 80 suspended 15 from the mounting in which the respective idle pulley 77 is arranged.

In order that the inking rolls and in fact each entire inking unit including the housing 23, reservoir 34, and the parts associated 20 therewith, may be adjusted transversely of the support 22, and thus adapting the machine to print upon the sides of boxes of different widths, fed between said impression rolls, the support 22 is provided with 25 upstanding portions 81 and screws 82 are threaded through these portions and bear against the wall of the housing beside the wall in which the opening 27 is formed and, in order that the housings may be guided in 30 their shifting adjustment, a headed stud 85 is provided upon the bottom of each housing and headed at its lower end, and this stud works in a slot 84 formed in the supporting member 22. Another slot 85 is 35 formed in each supporting member and the shaft upon which the inking roll 23 is mounted, is provided with a reduced lower end 86 which works in this slot, said lower end of the shaft engaging rotatably in an opening 40 87 in the bottom of the housing and the shaft having a reduced upper end 88 engaging rotatably in an opening 89 formed in the top of the housing.

What I claim is:—

45 1. In a box printing machine, spaced printing rolls for impressing matter on the opposite sides of a box, and means for feeding boxes successively between the rolls, the said means comprising parallel travelling chains, means operated by the box feeding means and including an abutment for operating the printing rolls, arms extending from the chains, and an abutment roller supported between the arms to engage the abutment at one end of a box.

50 2. In a box printing machine, spaced printing rolls for impressing matter on the opposite sides of a box, inking rolls mounted for surface contact with the printing rolls, means for supplying ink to the printing rolls, means for feeding a box between the printing rolls with the rolls in contact with the opposite sides of the box, means for rotating said printing rolls in consonance with 55 the speed of travel of the box between the

rolls, the said means comprising a gear rotatable with each roll, spaced rack bars meshing with the gears, and means for shifting said bars.

3. In a box printing machine, spaced 70 printing rolls for impressing matter on the opposite sides of a box, inking rolls mounted for surface contact with the printing rolls, means for supplying ink to the printing rolls, means for feeding a box between the 75 printing rolls with the rolls in contact with the opposite sides of the box, the said means comprising spaced shafts, sprocket gears upon the shafts, chains trained about said gears, means for imparting rotary motion to 80 one of said shafts, and abutment members extending between the chains to impart sliding movement to the box, and chain carried means engaging the abutment members for rotating said printing rolls in consonance 85 with the speed of travel of the box between the rolls.

4. In a box printing machine, spaced 90 printing rolls for impressing matter on the opposite sides of a box, inking rolls mounted for surface contact with the printing rolls, means for supplying ink to the printing rolls, means for feeding a box between the printing rolls with the rolls in contact with the opposite sides of the box, the said means comprising spaced shafts, sprocket gears upon the shafts, chains trained about said 95 gears, means for imparting rotary motion to one of said shafts, abutment members extending between the chains to impart sliding movement to the box, means for rotating said printing rolls in consonance with the speed of travel of the box between the rolls, the means for rotating the rolls comprising a gear rotatable with each roll, spaced rack 100 bars meshing with the gears, arms extending from the chains, and a roll supported between the arms and engageable with the said abutment member.

5. In a box printing machine, spaced 110 printing rolls for impressing matter on the opposite sides of a box, inking rolls mounted for surface contact with the printing rolls, means for supplying ink to the printing rolls, means for feeding a box between the printing rolls with the rolls in contact with the opposite sides of the box, the said means comprising spaced shafts, sprocket gears upon the shafts, chains trained about 115 said gears, means for imparting rotary motion to one of said shafts, abutment members extending between the chains to impart sliding movement to the box, means for rotating said printing rolls in consonance with the speed of travel of the box between the rolls, the means for rotating the rolls comprising a gear rotatable with each roll, spaced rack bars meshing with the gears, arms extending from the chains, and a roll supported 120 between the arms and engageable 125

120

with the said abutment member, and means for automatically returning the rack bars to their initial positions when the box has passed between the printing rolls.

5 6. In a box printing machine, spaced printing rolls for impressing matter on the opposite sides of a box, inking rolls mounted for surface contact with the printing rolls, means for supplying ink to the printing rolls, means for feeding a box between the printing rolls with the rolls in contact with the opposite sides of the box, the said means comprising spaced shafts, sprocket gears upon the shafts, chains trained about said 10 gears, means for imparting rotary motion to one of said shafts, abutment members extending between the chains to impart sliding movement to the box, means for rotating said printing rolls in consonance with the 15 speed of travel of the box between the rolls, the means for rotating the rolls comprising a gear rotatable with each roll, spaced rack bars meshing with the gears, arms extending from the chains, and a roll supported 20 between the arms and engageable with the said abutment member, and means for automatically returning the rack bars to their initial positions when the box has passed between the printing rolls, the said means 25 comprising cables connected to the rack bars, pulleys over which the cables are trained, and counter weights suspended from the 30 cables.

7. In a box printing machine, spaced 35 printing rolls for impressing matter on the opposite sides of a box, shafts supporting the printing rolls, bearings in which the ends of the shafts are rotatably mounted, tubular boxes in which the bearings are mounted 40 for movement toward and from the path of travel of the box to be printed, and compression springs in said boxes engaging the bearings and urging the same in the first mentioned direction, inking rolls mounted for 45 surface contact with the printing rolls, means for supplying ink to the printing rolls, means for feeding a box between the printing rolls with the rolls in contact with the opposite sides of the box, and means for 50 rotating said printing rolls in consonance with the speed of travel of the box between the rolls.

8. In a box printing machine, spaced 55 printing rolls for impressing matter on the opposite sides of a box, shafts supporting the printing rolls, bearings in which the ends of the shafts are rotatably mounted, tubular boxes in which the bearings are mounted for movement toward and from the path of 60 travel of the box to be printed, and compression springs in said boxes engaging the bearings and urging the same in the first mentioned direction, inking rolls mounted for surface contact with the printing rolls, 65 means for supplying ink to the printing

rolls, means for feeding a box between the printing rolls with the rolls in contact with the opposite sides of the box, means for rotating said printing rolls in consonance with the speed of travel of the box between the 70 rolls, and means for adjusting the tension of the said springs.

9. In a box printing machine, spaced printing rolls for impressing matter on the opposite sides of a box, shafts supporting 75 the printing rolls, bearings in which the ends of the shafts are rotatably mounted, tubular boxes in which the bearings are mounted for movement toward and from the path of travel of the box to be printed, and compression springs in said boxes engaging the 80 opposite sides of the bearings.

In testimony whereof I affix my signature.
DANTE O. TEMPESTINI.
